UNITED STATES PATENT OFFICE

158,713

WHEELED TOY

Joseph E. Brown, Rockwell, N. C.

Application May 10, 1948, Serial No. 146,262

Term of patent 3½ years

(Cl. D34—15)

To all whom it may concern:

Be it known that I, Joseph E. Brown, a citizen of the United States, residing at Rockwell, in the county of Rowan and State of North Carolina, have invented a new, original, and ornamental Design for a Wheeled Toy, of which the following is a specification, reference being had to the accompanying drawing, forming a part thereof.

I claim:

The ornamental design for a wheeled toy, substantially as shown.

JOSEPH E. BROWN.
